US00D916231S

(12) **United States Design Patent** (10) **Patent No.:** **US D916,231 S**
(45) **Date of Patent:** **** Apr. 13, 2021**

(54) **LID FOR SPRAY GUN**

(71) Applicant: **QINGDAO HANBO PLASTIC TECHNOLOGY CO., LTD.**, Qingdao (CN)

(72) Inventor: **Yun Xiao**, Jiaonan (CN)

(73) Assignee: **QINGDAO HANBO PLASTIC TECHNOLOGY CO., LTD.**, Qingdao (CN)

(**) Term: **15 Years**

(21) Appl. No.: **29/696,207**

(22) Filed: **Jun. 26, 2019**

(30) **Foreign Application Priority Data**

Jun. 4, 2019 (CN) 201930286524.5

(51) LOC (13) Cl. **23-01**

(52) U.S. Cl.

USPC **D23/202**

(57) **CLAIM**

The ornamental design for a lid for spray gun, as shown and described.

DESCRIPTION

FIG. 1 is a front perspective view of the lid for a spray gun;

FIG. 2 is a front view thereof;

FIG. 3 is a back view thereof;

FIG. 4 is a left view thereof;

FIG. 5 is a right view thereof;

FIG. 6 is a top view thereof;

FIG. 7 is a bottom view thereof; and,

FIG. 8 is a perspective view of the lid assembled along with other components of the spray gun.

The broken lines shown in the drawings depict portions of the lid for spray gun that form no part of the claimed design. The broken line showing of the spray gun cup in FIG. 8 forms no part of the claimed design.

1 Claim, 8 Drawing Sheets
